[57] ABSTRACT

[22] Filed: **Mar. 20, 1970**

A therapeutic bath has ultrasonic acoustic transducers around the outer surface thereof, which uniformly oscillate a liquid within the bath. A part of the body suffering from a musculoskeletal disorder is placed in the bath. The power of the oscillations is adjusted to the individual patient. The liquid may include a medication to simultaneously treat and clean an open wound. Treatment is applicable to both humans and animals.

ULTRASONIC TREATMENT DEVICE AND METHODS FOR USING THE SAME

BACKGROUND OF THE INVENTION

The present invention relates to an ultrasonic therapeutic treatment system. More specifically, the present invention relates to therapeutic treatment for relieving symptoms of certain musculoskeletal conditions of humans and animals. Furthermore specifically, the present invention relates to the therapeutic treatment of open wounds. Even more specifically, the present invention relates to such treatment by means of an ultrasonic bath, whereby the entire bath is subject to ultrasonic oscillations and the power of the ultrasonic oscillations is variable to adapt to the individual patient.

In the past there has been a great need for relieving symptoms of a number of musculoskeletal disorders, such as periostitis, contusions, sprains, strains, sesamoiditis, apophysitis, bunions, callousitis, tenosynovitis, various types of arthritis such as osteo arthritis, calcaneal spurs, neuralgia, fractures and bursitis. A number of attempts have been made in the past to develop therapeutic treatments for relieving the symptoms of certain of these disorders.

One form of such a prior art treatment involves a system to apply vibrations directly or through a coupling such as grease to parts of the body. However, such a treatment has a very limited degree of application and success. A later form of treatment comprises a therapeutic bath with a transducer located within the bath. However, this form of treatment also met with limited application and success. A primary problem with this system is that the oscillations are made uneven throughout the bath, and therefore the effect of the treatment varied greatly within the bath.

All of the above methods of treatment suffer from certain inherent disadvantages in addition to the above listed disadvantages. Each patient is subjected to the same treatment. However, it has been found that each patient is not susceptible to the same treatment. This is due to differences in bone structure, skin flesh density, water content, and other musculoskeletal traits of the individual.

With these disadvantages in mind, it is an object of the present invention to provide therapeutic treatment to relieve the symptoms of certain musculoskeletal disorders, which treatment provides vastly improved results over the above-mentioned prior art treatments.

Furthermore, it is an object of the present invention to provide such treatment having a much greater field of application than prior art treatments.

Additionally, it is an object of the present invention to provide therapeutic treatment which is adaptable to the individual needs and limitations of each patient.

It is still a further object of the present invention to provide such a therapeutic treatment to relieve the symptoms of certain disorders in both humans and in animals.

It is to be understood that the scope of the present invention includes the treatment of all musculoskeletal disorders. For instance, the present invention encompasses the treatment of bone disorders such as fractures, and also disorders which relate to and effect bones such as calcaneal spurs and apophysitis. The present invention also encompasses the treatment of all types of muscle disorders such as contusions, membrane disorders such as periostitis, skin disorders such

as callousitis, tendon disorders such as tenosynovitis, and bursa disorders such as bursitis and bunions. Furthermore, the present invention encompasses the treatment of disorders relating to and/or effecting bone and muscle, cartilage, ligament or nerve such as sprains, strains, sesamoiditis, various types of arthritis such as osteo arthritis and Morton's neuralgia.

These objects are achieved in accordance with the present invention by ultrasonically vibrating a therapeutic bath by means of ultrasonic acoustical transducers attached to the outside of the bath. This enables the entire bath to be uniformly oscillated. Such oscillations provide therapeutic relief of the symptoms of certain disorders. Means are provided to vary the power of the

oscillations over a wide range. This variation of power allows each treatment to be adapted to the individual musculoskeletal limitations of the patient. Therefore, the conditions of treatment for each patient may be adjusted to provide the most effective treatment. This treatment will relieve the symptoms of certain musculoskeletal conditions in humans, and also in horses, cattle, dogs, cats and other similar livestock and pets.

Similarly, in the past there has been a great need for a method of debridement whereby open wounds may be cleaned and treated simultaneously. In the past, such therapeutic treatment and cleaning has consisted of a meticulous surgical debridement, such as wiping or sponging the open wound with a medication. However, it has been difficult by the use of such treatment to remove implanted dirt and debris from the wound.

Therefore, it is a further object of the present invention to provide a vastly improved therapeutic treatment of open wounds.

Such objects are achieved in accordance with the present invention by providing a medication in the ultrasonic bath. The ultrasonic bath performs cleaning of the wound, and simultaneously applies medication to the wound. The power of the bath is variable to adapt both to the limitations of each patient, and also to the severity of the particular wound.

Additionally, the present invention provides such a cleaning and therapeutic treatment whereby an acoustically transparent container surrounds the open wound, and contains medication which is in contact with the open wound. The wound and the container are then placed within the bath. Simultaneous cleaning and medication are performed in a similar manner as previously described.

Other objects and features of the invention will be made clear by the following description, taken together with the accompanying drawings.

BRIEF DESCRIPTION OF THE DRAWINGS

FIG. 1 is a schematic diagram of a therapeutic treatment device in accordance with the present invention;

FIG. 2 is a diagram of a preferred portable therapeutic treatment unit in accordance with the present invention; and

FIG. 3 is a diagram, partly in section, of a modified embodiment of the present invention for use in the simultaneous treatment and cleaning of open wounds.

With reference now to the drawings, a device will be described which will conveniently be used to perform the treatment of the present invention. In FIG. 1 is shown a bath 1 which is susceptible to ultrasonic oscillation. Around the outer surface of the bath 1 are provided a plurality of ultrasonic transducers 2. Transduc-

ers 2 are connected in a known manner through frequency oscillator 4 to an AC source 3. When power is supplied from source 3 to ultrasonic transducers 2, the liquid within the bath 1 is uniformly oscillated at a desired power and frequency. In order to adapt the power of the oscillations to the individual patients, variable power control 5 is provided in the control circuit. Control device 5 may be any such known device, or any commercially available such device. They are connected within the circuit in a known manner. By the provision of the control element 5, the power of the oscillation of the bath may be independently controlled and adjusted.

With reference now to FIG. 2, an example of a practical device embodying the present invention is shown. The treatment device described with reference to FIG. 1 is conveniently mounted in a portable cart generally indicated at 10. Cart 10 includes handle 11 and wheels 12 for portable movement. Bath 1, having transducers 2 mounted on the outer surface thereof, is conveniently and conventionally mounted within cart 10. Electronic power and control circuit 6, which includes frequency oscillator 4 and variable power control 5, is also conveniently mounted on cart 10.

It is to be understood that the practical embodiments of the present invention may be other than that specifically shown in FIG. 2. For instance, the cart 10 may have a different shape than that shown. Furthermore, the device may be mounted permanently rather than in a portable unit.

Furthermore, it is to be understood that the bath 1 may be of various shapes and adapted to receive various limbs and parts of the body undergoing treatment. For instance, the bath 1 may be particularly shaped to receive a foot, or a leg, or a hand, or an arm, or an elbow. Thus, it is to be seen that the scope of the present invention includes more than the diagrammatic shape of bath 1 shown in the figures.

Furthermore, it is to be understood that the present invention may include variable control units of a known type. For instance, as mentioned above, the frequency oscillator and transducers may be any which are commercially available and known in the art, for instance of polycrystalline ceramic material such as barium titanate or zirconium titanate. One example is the "Sono" type, manufactured by Linden Laboratories.

The variable power control may be any which is known and commercially available in the art. One such example is the "Powerstat" (7.5 amps/100-140V) manufactured by Superior Electric Co., of Springfield, Ill.

The operation of the above device will now be described. The part of the body which is to undergo treatment is comfortably placed within the bath. The transducers cause the liquid in the bath to oscillate, whereby acoustic energy is conveyed throughout the liquid in the bath and the part of the body within the bath. A sufficient number of transducers are used to insure that the energy is uniformly conveyed throughout the liquid in the bath and the part of the body within the bath at the desired power level.

It has generally been found that the greater the energy applied to the part of the body undergoing treat-

ment, the more successful will be the treatment. Thus, the variable power control is then adjusted to raise the power level as high as possible. When the power reaches the level at which there appears discomfort to the patient, the power level is slightly reduced. The practical range of power depends upon the patient, and may vary a great deal up to, for instance, a level of 1.0 watt per square centimeter of skin within the bath. However, it has been found that the most practical range is from 0.30 to 0.70 Watt/cm² of skin within the bath.

The frequency of oscillation of the acoustic energy may be set at any desired level, usually within the range of 50 to 250 kilocycles. A particularly effective setting is 100 kc, with a tolerance of $\pm$ 20 kc. Thus, according to this embodiment, the oscillator would be designed for 100 kc, and within commercial tolerances would oscillate at a frequency in the range of from 80 to 120 kc.

The time length of each treatment may practically range from 3 or 4 minutes up to 10 minutes or more. It has been found that the treatment embodying the present invention is effective very rapidly. It has also been found that usually after 10 minutes of treatment, no additional benefits accrue. The number of treatments necessary vary a great deal, and depend on the individual patient, on the particular condition being treated, and upon the severity of the symptoms of the condition. It has been found that satisfactory results may occur after only a single treatment. It has also been found that good results have required as many as eleven treatments. It is conceivable of course, that relief of symptoms may take more than eleven treatments.

The composition of the bath may include any liquid which is sensitive to the transmission of acoustical energy, and which may be beneficial to the treatment of the particular condition. Water alone may be used, or various aqueous, oil or wax solutions may be used.

The temperature of the bath is not critical, although it has been found generally that warmer temperatures are helpful. The main consideration would be the comfort of the patient.

EXAMPLE 1

A patient suffering from a condition medically diagnosed as periostitis tibial tuberosity at the ankle, an old injury, was treated in accordance with the present invention. The patient, prior to treatment, suffered pain upon contact with shoes, or upon digital pressure. The ankle was placed in a bath in accordance with the present invention. The power was adjusted to 0.46 Watt/cm² of skin with in the bath. This was found to be the maximum acceptable comfortable limit for this patient. The frequency of the ultrasonic oscillations was between 80 and 90 kilocycles. The treatment was continued for 10 minutes. Two treatments such as described were performed on the patient. After the second treatment, the pain was completely gone and the patient could walk and wear shoes without pain.

A further patient was treated for symptoms of a similar condition in accordance with the present invention. The results are summarized in Table 1.

TABLE 1

PRE-TREATMENT MEDICAL DIAGNOSIS	SYMPTOMS OF CONDITION	POWER WATT/cm ²	FRE- QUENCY (KC)	LENGTH OF TREAT- MENT (MIN)	NO. OF TREAT- MENTS	EFFECT OF TREATMENT ON SYMPTOMS
Periostitis Navi-cular - right foot	Pain upon pressure and upon motion	0.49-0.57	80 to 90	8	9	Pain subsided

Thus it is shown that treatment in accordance with the present invention is successful in the relief of symptoms of periostitis.

EXAMPLE 2

A patient suffering from a condition medically diagnosed as contusion of the first metatarso-phalangeal joint was treated in accordance with the present invention. The patient evidenced pain and edema and restricted motion. The particular joint was placed in the ultrasonic bath as above described. Power was adjusted to 0.37 Watt/cm². The frequency of the ultrasonic oscillations was between 80 and 90 kilocycles. The length of each treatment was 10 minutes. Three treatments were given, and at the end of the third treatment the pain and edema had subsided and motion was completely restored.

Other patients suffering from similar contusions underwent similar treatment, the results of which are summarized in Table 2.

Thus, it is seen that treatment in accordance with the present invention significantly relieves the symptoms of severe contusions.

15

EXAMPLE 3

A patient suffering from a condition medically diagnosed as right ankle sprain was treated in accordance with the present invention. The symptoms of the patient's condition included massive edema, ecchymosis, weight bearing very painful. The power was adjusted to 0.57 Watt/cm² after the patient's ankle was placed in the bath. The frequency of the oscillations was between 80 to 90 kilocycles. Each treatment lasted 8 minutes. Seven treatments were conducted, and after the seventh treatment, the edema had been reduced, there was no pain on locomotion, and the ecchymosis had been absorbed. Other patients suffering from similar conditions were treated in accordance with the present invention. The results of these treatments are summarized in Table 3.

TABLE 2

PRE-TREATMENT MEDICAL DIAGNOSIS	SYMPTOMS OF CONDITION	POWER WATT/cm ²	FRE- QUENCY (KC)	LENGTH OF TREAT- MENT (MIN)	NO. OF TREAT- MENTS	EFFECT OF TREATMENT ON SYMPTOMS
Severe Contusion Lt. Heel	Pain upon walking	0.55	80 to 90	8	5	Pain completely absent
Severe Contusion 5th toe right foot	Pain and edema	0.57	80 to 90	10	2	Pain ceased and reduction of edema
Severe Contusion of foot	Ecchymosis and pain as well as edema	0.57	85	5	2	Absorption of edema and disappearance of ecchymosis
Contusion-second, third and fourth metatarsal	constant pain and edema	0.57	80 to 90	5	6	Complete absence of pain and edema. No sensitivity anywhere in foot
Contused Sesamoid Bone left foot	Pain at ball of great toe joint on weight bearing. Edema of area (left foot only)	0.52	80 to 90	8	5	Edema subsided. Pain reduced to negative except when walking barefooted. Change of weather noticeably in area of condition treated
Contusion severe 2nd, 3rd and 4th Metatarsal head area right foot	Edema-Extensive-Pain on contact with shoe and digital pressure	0.57	80 to 90	8	6	Edema and pain subsided

TABLE 3

PRE-TREATMENT MEDICAL DIAGNOSIS	SYMPTOMS OF CONDITION	POWER WATT/cm ²	FRE- QUENCY (KC)	LENGTH OF TREAT- MENT (MIN)	NO. OF TREATMENTS	EFFECT OF TREATMENT ON SYMPTOMS
Sprain mid-tarsal area right foot	Pain on weight bearing limited motion	0.61	80-90	8	3	<u>Absence of pain</u> motion normal
Sprain rt. 1st carpal metacarpal jt.	Pain no power in grip	0.55	80-90	10	5	Pain eased to point of occa- sion twinge Free from pain
Chronic sprain left	constant ache and sensitiv- ity	0.66	80-90	8-10	5	
Sprain midtarsal joints	Pain on pres- sure and edema	0.41	80-90	10	3	Absence of pain and reduction of edema completely
Chronic sprain of rt. ankle	Pain and edema on standing	0.69	80-90	8-10	4	No edema, pain completely re- lieved. Function excellent
Sprain right ankle (lateral)	Pain and Edema right ankle Walking is possible with a cane.	0.49-0.57	80-90	10	7	Pain and Edema subsided. Patient walked without cane after 2nd treatment Edema subsided. Pain eliminated
Sprain midtarsal area right foot	Pain causing limp upon walking and pain on any pressure. Edema at in- step	0.53-0.57	80-90	10	3	
Sprain left ankle	Edema-Eccymo- sis extensive extremely limited motion	0.66	80-90	10	5	Edema subsided- Motion unrestric- ted-Eccymosis faded in one week

Thus, it is seen that the treatment of sprains, in accordance with the present invention, significantly eliminates the symptoms of such conditions.

EXAMPLE 4

A patient suffering from a condition medically diagnosed as post-polio-myelitis plantar fascia strain of the right foot was treated in accordance with the present invention. The symptoms of the condition were severe pain and edema, patient almost nonambulatory. The patient's foot was placed in a bath in accordance with the present invention. The power level was adjusted to 0.55 Watt/cm² and the frequency of oscillations was between 80 to 90 kc. The time length of each treatment was 8-10 minutes. After the end of the sixth treatment, the pain and edema had disappeared.

Similar treatments were conducted on patients suffering from similar conditions. Results of these treatments are summarized in Table 4.

35 Thus it is seen that treatment in accordance with the present invention relieves the symptoms of strains.

EXAMPLE 5

40 A patient suffering from a condition medically diagnosed as sesamoiditis of the left foot was treated in accordance with the present invention. The symptoms of the condition were chronic pain and edema. The foot was placed in a bath in accordance with the present invention as described above. The power level was adjusted to 0.64 Watt/cm², and the frequency of oscillations was between 80 to 90 kc. The length of each treatment was 8-10 minutes. After the end of the fourth treatment, the pain was gone and the edema was completely absorbed.

45 50 Patients suffering from similar conditions were treated in accordance with the present invention. The results of these treatments are summarized in Table 5.

TABLE 4

PRE-TREATMENT MEDICAL DIAGNOSIS	SYMPTOMS OF CONDITION	POWER WATT/cm ²	FRE- QUENCY (KC)	LENGTH OF TREAT- MENT (MIN)	NO. OF TREATMENTS	EFFECT OF TREATMENT ON SYMPTOMS
Plantar fascia strain; result of pes cavus edema	Pain on stand- ing and walk- ing. Edema	0.49	80-90	8-10	7	<u>Absence of</u> edema complete- ly. Freedom from pain com- pletely
Chronic Plantar Fascia strain (Fascitis) both feet	Extreme pain upon any use of feet	0.41-0.49	80-90	8	8	Pain subsided— Activities (Athletic resumed)

TABLE 5

PRE-TREATMENT MEDICAL DIAGNOSIS	SYMPTOMS OF CONDITION	POWER WATT/cm ²	FRE- QUENCY (KC)	LENGTH OF TREAT- MENT (MIN)	NO. OF TREATMENTS	EFFECT OF TREATMENT ON SYMPTOMS
Sesamoiditis left foot first Metatarsal head	Unable to bear weight on forefoot pain on flexion and extension	0.61	80-90	10	4	Pain free-weightbearing normal motion unrestricted
Sesamoiditis(Bifurcated) right foot	Pain at ball of foot upon standing and walking and upon extension of great toe	0.57-0.61	80-90	8	9	Pain on extension ceased
Sesamoiditis(Bifurcated) right foot	Pain on standing or extension of great toe	0.57-0.61	80-90	8	7	Pain subsided motion was normal and painless

Thus, it is seen that treatment in accordance with the present invention relieves the symptoms of sesamoiditis.

EXAMPLE 6

A patient suffering from a condition medically diagnosed as apophysitis of the left heel was treated in accordance with the present invention. The symptoms of the condition were pain on weight bearing and upon physical activities. The heel was placed in the bath in accordance with the present invention. The power level was varied between 0.49 and 0.53 Watt/cm², and the frequency was between 80 to 90 kc. The length of each treatment was 8 minutes, and after the end of the third treatment the pain had subsided.

A further patient suffering from a similar condition was treated in accordance with the present invention. The results of such treatment are summarized in Table 6.

25

EXAMPLE 8

A patient suffering from a condition medically diagnosed as multiple callousitis bilateral was treated in accordance with the present invention. Symptoms of the condition were pain at metatarsal areas of both feet. 30 The feet were placed in a bath and the power was adjusted to from 0.59 to 0.61 Watt/cm². The frequency of oscillation was between 80 and 90 kc. The length of each treatment was 8 minutes. At the end of the third treatment, the inflammation had been reduced. The 35 ache, however, although decreased, remained present, due to the foot structure of the patient.

Thus it is seen that treatment in accordance with the present invention is successful in relieving symptoms of callousitis.

TABLE 6

PRE-TREATMENT MEDICAL DIAGNOSIS	SYMPTOMS OF CONDITION	POWER WATT/cm ²	FRE- QUENCY (KC)	LENGTH OF TREAT- MENT (MIN)	NO. OF TREATMENTS	EFFECT OF TREATMENT ON SYMPTOMS
Apophysitis left heel	Pain on walking and running and on digital pressure	0.49-0.55	80-90	8	5	Pain upon walking ceased. Running was forbidden

Thus, it is seen that treatment in accordance with the present invention is successful in relieving the symptoms of apophysitis.

EXAMPLE 7

A patient suffering from a condition medically diagnosed at Tailor's bunion of the left foot, head of the fifth metatarsal, was treated in accordance with the present invention. The symptoms were edema and erythema, right 5th metatarsal head. The foot was placed in a bath and the power level was adjusted to 0.53 to 0.61 Watt/cm². The frequency of oscillations was between 80 to 90 kc. Each treatment last 8 minutes. At the end of the fourth treatment, the pain has subsided. The enlarged joint however, being bone, did not decrease.

55

EXAMPLE 9

A patient suffering from a condition medically diagnosed as tendonitis posterolateral tibial muscle of the right foot was treated in accordance with the present invention. The symptoms of the condition were pain upon motion, motion restricted. The foot was placed in a bath in accordance with the present invention. The power level was adjusted to 0.52 Watt/cm², and the frequency was between 80 and 90 kc. Each treatment lasted 10 minutes. At the end of the fourth treatment, the pain had disappeared, and motion was completely unrestricted.

65

Patients suffering from conditions similar to that above were treated in accordance with the present invention. The results of these treatments are summarized in Table 7.

TABLE 7

PRE-TREATMENT MEDICAL DIAGNOSIS	SYMPTOMS OF CONDITION	POWER WATT/cm ²	FRE- QUENCY (KC)	LENGTH OF TREAT- MENT (MIN)	NO. OF TREATMENTS	EFFECT OF TREATMENT ON SYMPTOMS
Tendonitis-Extensor Hallucis Longus left foot Hallux Valgus left foot	Pain on motion extension and flexion of great toe left foot	0.43-0.61	80-90	10	6	Pain subsided- Motion returned to normal and
Chronic Hallux Valgus right foot	Pain in shoes and Erythema of area	0.57	80-90	8	5	Edema reduced- pain eliminated
Tenosynovitis right foot-extensor Hallugis Longus Mosue	Pain on exten- sion of great toe right foot upon either active or passive motion. Range of motion limited due to pain	0.55	80-90	8	8	Pain completely absent. Motion unlimited
Tenosynovitis right tendon achilles	Extreme pain on motion Edema in ankle area	0.53-0.70	80-90	8	7	Pain and Edema subsided

Thus it is seen that treatment in accordance with the present invention is successful in relieving symptoms of tendonitis and similar conditions.

EXAMPLE 10

A patient suffering from a condition medically diagnosed as osteo arthritis of both feet was treated in accordance with the present invention. Symptoms of the

25 condition were pain and edema in joint areas, stiffness and limited motion. Both feet were placed in the bath in accordance with the present invention. Power was adjusted to 0.41 Watt/cm², and frequency was between 80 and 90 kc. Each treatment lasted 8 minutes. At the end of the seventh treatment, the pain and edema had been decreased, and motion was increased.

30 Other patients suffering from similar conditions were treated in accordance with the present invention. The results of these treatments are summarized in Table 8.

TABLE 8

PRE-TREATMENT MEDICAL DIAGNOSIS	SYMPTOMS OF CONDITION	POWER WATT/cm ²	FRE- QUENCY (KC)	LENGTH OF TREAT- MENT (MIN)	NO. OF TREATMENTS	EFFECT OF TREATMENT ON SYMPTOMS
Osteo Arthritis both feet Metatarsal Phalan- geal area Hallux Valgus (right) chronic Edema	Pain upon walk- ing Edema chronic Pain-intermit- tent edema	0.55	80-90	10	4	No pain - Re- duction of Edema
Osteo Arthritis Phalan- geal Metatarsal joints bilateral	Pain on digi- tal pressure and when stand- ing for short periods	0.53-0.59	80-90	8-10	4	Pain decreased. No edema
Osteo Arthritis right ankle	Pain and aching after walk- ing or standing	0.57-0.61	80-90	10	2	Pain subsided and ache disappeared
Osteo Arthritis mid Tarsal joints bilater- al	Pain upon walking and standing	0.49-0.52	80-90	8	5	Patient felt pain ache had subsided and further treat- ment wasn't nec- essary Pain subsided upon walking
Arthritis-2nd right Metatarsal	Pain on pres- sure (lateral) or dorsal) flex- ion and exten- sion Edema	0.59	80-90	8	5	Motion unrestric- ted and pain free. Edema absorbed
Osteo Arthritis-Digital both feet	Pain on motion and when re- tired Edema of toes	0.49	80-90	10	5	Pain and Edema subsided
Osteo Arthritis both feet	Pain on walk- ing and stand- ing	0.49-0.57	80-90	8	6	Pain decreased to point of com- fort

Thus it is seen that treatment in accordance with the present invention is successful in relieving the symptoms of osteo arthritis.

EXAMPLE 11

A patient suffering from a condition medically diagnosed as calcaneal spur of the left foot was treated in accordance with the present invention. Symptoms of the condition were pain upon walking and pain upon standing after rest. The foot was placed in the bath and the power was adjusted to 0.46 Watt/cm². The frequency was between 80-90 kc. The length of each treatment was 10 minutes. At the end of the sixth treatment, the pain had completely subsided.

Patients suffering from similar conditions were treated in accordance with the present invention. The results of these treatments are summarized in Table 9.

nosed as Morton Neuralgia bilateral was treated in accordance with the present invention. Symptoms of the condition were pain after wearing shoes. The feet were placed in a bath and the power level was adjusted to 0.66 Watt/cm². Frequency was between 80-90 kc. The length of each treatment was 8-10 minutes. At the end of the third treatment, the pain had decreased.

Thus, it is seen that treatment in accordance with the present invention is successful in relieving the symptoms of neuralgia.

EXAMPLE 13

A patient suffering from a condition medically diagnosed as fracture proximal phalanx of the left third toe was treated in accordance with the present invention. Symptoms of the condition were pain and edema upon

TABLE 9

PRE-TREATMENT MEDICAL DIAGNOSIS	SYMPOTMS OF CONDITION	POWER WATT/cm ²	FRE- QUENCY (KC)	LENGTH OF TREAT- MENT (MIN)	NO. OF TREATMENTS	EFFECT OF TREATMENT ON SYMPTOMS
Bilateral Calcaneal spurs	Extreme pain on standing and especially after resting	0.46	80-90	10	11	Pain subsided, walking and standing provides no sensitivity
Plantar calcaneal spur	Pain on digital pressure and weight-bearing	0.62	80-90	8-10	4	Pain subsided and heel aches only after extensive walking
Calcaneal spur(left)	Pain on standing, walking, and digital pressure	0.62	80-90	8-10	6	Pain subsided, and recurs only periodically after extended standing or walking
Calcaneal spur left foot	Pain upon standing and walking	0.57	80-90	10	7	Pain subsided and walking and stand-creates no discomfort
Calcaneal spur right foot Plantarly	Pain-needle sharp upon standing or walking	0.53	80-90	8 increased to 10	5	Pain subsided and symptom free
Calcaneal spurs-Plantarly both feet	Pain upon arising and on walking or standing	0.52	80-90	8	8	Pain subsided. Walks with ease.
Bilateral Calcaneal spur Plantarly	Pain upon arising and walking or standing	0.66	80-90	8-10	6	Pain ceased
Calcaneal spur-Plantarly both feet	Standing and walking caused extreme pain	0.64	80-90	10	6	Pain subsided after 2nd treatment and patient was pain free after completion of 6th treatment
Calcaneal spur left foot plantarly	Pain on walking or standing especially upon arising	0.57	80-90	8	5	Pain eased - No pain when arising, walking is comfortable

Thus, it is seen that treatment in accordance with the present invention is successful in relieving the symptoms of calcaneal spurs.

EXAMPLE 12

A patient suffering from a condition medically diag-

weight bearing. The foot was placed in a bath and the power level was adjusted to 0.46 Watt/cm². The frequency was between 80 and 90 kc. The length of each treatment was 8-10 minutes. At the end of the sixth treatment, the edema had been absorbed, and the pain has subsided. The patient was able to ambulate.

Patients suffering from similar conditions were treated in accordance with the present invention. The results of these treatments are summarized in Table 10.

area of the left foot was treated in accordance with the present invention. The symptoms of the condition were pain on digital pressure, and slight edema. The foot was

TABLE 10

PRE-TREATMENT MEDICAL DIAGNOSIS	SYMPTOMS OF CONDITION	POWER WATT/cm ²	FRE- QUENCY (KC)	LENGTH OF TREAT- MENT (MIN)	NO. OF TREATMENTS	EFFECT OF TREATMENT ON SYMPTOMS
Fracture 5th toe(right) three wks. old. Pain and edema	Pain on pres- sure and when walking. Edema	0.61	80-90	8-10	3	Edema reduced. No pain while wearing foot- gear or when walking
Post fracture Fibrosis and Edema of ankle. Left loss of motion(ex- tension and flexion)	Pain on weight bearing. Edema after walking. Lack of mo- tion even with passive exer- cise	0.53	80-90	10	6	Ankle has motion. Fibrosis dis- solved. Edema eliminated and pain free
Fracture Proximal Phalanx 4th toe- Duration 3 weeks	Pain on weight bearing and Edema	0.52	80-90	8	4	Edema subsided- Pain absent
Fracture,Proximal Pha- lanx right 4th toe	Pain upon flex- ion and exten- sion	0.55	80-90	8	4	Pain subsided- able to ambulate painlessly
Transverse fracture 5th toe right foot Prox. Phalanx	Pain on pres- sure either shoe or digital con- dition has been present for 2 weeks prior to treatment	0.57	80-90	8	3	Edema subsided pain subsided

Thus it is seen that treatment in accordance with the present invention is successful in relieving the symptoms of fractures.

EXAMPLE 14

A patient suffering from a condition medically diagnosed as adventitious bursitis metatarsal phalangeal

placed in the bath, and the power level was adjusted to 0.53 Watt/cm². The frequency was between 80-90 kc. 35 The length of each treatment was 8 minutes. At the end of the fourth treatment, all pain and edema had subsided.

Patients suffering from similar conditions were treated in accordance with the present invention. The 40 results of these treatments are summarized in Table 11.

TABLE 11

PRE-TREATMENT MEDICAL DIAGNOSIS	SYMPTOMS OF CONDITION	POWER WATT/cm ²	FRE- QUENCY (KC)	LENGTH OF TREAT- MENT (MIN)	NO. OF TREATMENTS	EFFECT OF TREATMENT ON SYMPTOMS
Bursitis-Head of 5th Metatarsal Lt(Tailor Bunion)	Pain and Edema of Area, Erythema	0.61	80-90	8	6	Pain,Edema and Erythema Absol- ved
Bursitis-Navicular Tubercl Lt. Foot	Pain when wear- a shoe or slipper,Edema and Erythema	0.49	80-90	8	4	Edema and pain subsided. Slight erythema present but area was gener- ally normal
Bursitis sesamoid right first metatarsal head	Edema and ex- treme pain on weight-bearing	0.32	80-90	8-10	3	Absorption of edema and com- plete absence of pain
Adventitious Bursitis right foot Metatarso- Phalangeal joints	Pain on walking Edema at the base of the toes	0.62	80-90	10	4	Edema subsided- pain subsided
Bursitis front metatar- sal head of first meta- tarsal	Pain on walk- ing or run- ning	0.32	80-90	8-10	3	Pain subsided
Posterior Calcaneal Bursitis right foot	Pain on shoe pressure as well as digi- tal pressure	0.70	80-90	8	5	Pain subsided
Bursitis 5th toe left foot beneath Kerotosed tissue and Edema	Pain upon wearing any shoe	0.57-0.61	80-90	8	6	Pain and Edema subsided.Shoe no longer caused pain

TABLE 11—Continued

PRE-TREATMENT MEDICAL DIAGNOSIS	SYMPTOMS OF CONDITION	POWER WATT/cm ²	FRE- QUENCY (KC)	LENGTH OF TREAT- MENT (MIN)	NO. OF TREATMENTS	EFFECT OF TREATMENT ON SYMPTOMS
Bursitis right foot 1st Metatarsal joint	Pain when flexing foot or digital pressure	0.66	80-90	8	6	Pain free-Enlargement did not reduce Edema subsided
Bursitis-left calcaneal area Posterior	Chronic pain or flexion or extension with shoe on-Edema	0.41-0.49	80-90	8	5	Pain ceased on motion or pressure
Bursitis right achilles tendon	Pain on motion (flexion and extension of foot)	0.32-0.41	80-90	8	5	Motion is painless and full motion freely accomplished
Posterior Calcaneal Bursitis left foot	Pain and Edema left foot	0.49-0.52	80-90	8	6	Pain and Edema absorbed
Bursitis-right foot 5th Metatarsal head	Extreme pain, Erythema and Edema	0.49-0.57	80-90	10	5	Pain-Edema and Erythema eliminated
Adventitious Bursitis-Metatarso-Phalangeal joints both feet	Pain-extreme upon standing or walking. Edema of forefoot	0.57-0.67	80-90	10	4	Pain subsided. Edema absorbed
Bursitis right 5th metatarsal head (known also as Tailor's Bunion) Posterior Calcaneal Bursitis-Bilateral	Edema-slight and pain when wearing shoes Pain-Constant and severe Edema and Rubor of the area	0.57 0.49	80-90 80-90	10 8 to 10 gradually increased	3 9	Pain free and Edema absorbed Edema and Rubor absorbed and pain completely subsided. Shoes again could be worn comfortably

Thus it is seen that treatment in accordance with the present invention is successful in relieving the symptoms of bursitis.

The present invention is furthermore applicable to the treatment of other similar disorders than those specifically mentioned. Additionally, although the above examples all involve the treatment of humans, it is to be understood that the scope of the present invention encompasses the treatment of similar disorders in horses, cattle, dogs, cats and other livestock and pets. For instance, it is to be understood that a race horse suffering from a sprained knee joint could readily be treated in accordance with the present invention. This example is not meant to be limiting, however, since it is further to be understood that virtually any animal could be treated for any of the above specific disorders or similar related disorders.

It is also to be understood that the scope of the present invention encompasses the simultaneous treatment and cleaning of open wounds. As previously discussed there are great practical difficulties in thoroughly cleaning and treating open wounds. For instance, it is difficult by mere surgical debridement such as wiping or sponging of the wound to eliminate all debris or dirt therefrom. However, by employing the concept of the present invention, an open wound no matter how severe and dirty may be cleaned and treated simultaneously. Furthermore, such treatment and cleaning may be carried out more thoroughly and quickly than by any previously known method.

For instance, in this embodiment of the invention the liquid used in the bath shown in FIGS. 1 and 2 may include a medication. As the bath is ultrasonically vi-

brated, the wound is cleaned and simultaneously the medication is applied. The power of the ultrasonic vibrations is adjusted as described above. However, in addition to the discomfort of the patient, other limitations of the power include the severity of the wound and the amount of debris and dirt in the wound.

Often times, however, it may not be desirable to subject the open wound to the liquid bath. This may be for hygienic reasons. Therefore, in accordance with a further embodiment of the present invention, the advantages of the present treatment may be retained while isolating the open wound from the liquid in the bath. As shown in FIG. 3, open wound 20 is surrounded by an acoustically transparent container 21. Container 21 contains medication 22 which surrounds and covers wound 20 and which is also acoustically transparent. Container 21 may be made of any convenient material, the only requirement being that it be capable of transmitting acoustic vibrations. Examples of such material are polyethylene or polypropylene from 3-10 mils thick. The limb with the wound and the container are placed together in the bath. Treatment is then performed as described above. The ultrasonic oscillations are transmitted from the bath through container 21 and medication 22 to simultaneously clean and treat wound 20.

Although several embodiments of the invention have been described in detail, such description is intended to be illustrative only, since many details of the performance and construction of the invention may be altered or modified without departing from the spirit or scope thereof.

What is claimed is:

1. A therapeutic treatment device comprising a bath adapted to contain a therapeutic liquid; at least one acoustic transducer means attached to said bath for conveying uniform acoustic energy through said liquid at a uniform ultrasonic frequency; means operatively connected to said transducer means to selectively adjust the power of said energy to a uniform level up to 1.0 Watt/square centimeter of surface being treated within said liquid; and an acoustically transparent container adapted to contain a medication and surround an open wound, and adapted to be immersed in said liquid.

2. A device as claimed in claim 1, wherein said transducer oscillates at a frequency in the range of from 50 to 250 kilocycles.

3. A device as claimed in claim 1, wherein said transducer oscillates at a frequency of 100 ± 20 kilocycles, and said means for adjusting power is variable between 0.30 and 0.70 Watt per square centimeter of surface within said liquid.

4. A device as claimed in claim 1, wherein said bath is adapted in shape and size to accomodate the part of the body undergoing therapeutic treatment.

5. A device as claimed in claim 1, wherein said bath

and adjusting means are mounted on a movable cart, whereby said device is portable.

6. A method for the simultaneous treatment and cleaning of an open wound of a patient comprising placing said wound in a solution containing a medication within an acoustically transparent container surrounding said wound; placing said container in an ultrasonically oscillating bath; conveying uniform acoustic energy at a uniform ultrasonic frequency from said ultrasonically oscillating bath through said container and to said solution; and selectively adjusting the power of said energy up to the maximum comfort level of said patient while maintaining said uniform frequency, said level being no higher than 1.0 Watt/square centimeter of surface being treated in said bath.

7. A method as claimed in claim 6, wherein said frequency of said oscillations is in the range of from 50 to 250 kilocycles.

8. A method as claimed in claim 6, wherein said power is raised to from 0.30 to 0.70 Watt square centimeter of the surface of the body of said patient within said solution and the frequency of said oscillations is 100 ± 20 kilocycles.
